UNITED STATES PATENT OFFICE

FRANK E. BROWN, OF MILWAUKEE, WISCONSIN, ASSIGNOR TO HARNISCHFEGER CORPORATION, OF MILWAUKEE, WISCONSIN, A CORPORATION OF WISCONSIN

HOIST-LINE FAIR-LEAD

Application filed January 21, 1928. Serial No. 248,288.

- This invention relates to a fair lead especially designed for use with the hoist lines of back fillers or similar excavating machines other than the full revolving type.
- As is well known, back fillers comprise a frame mounted on suitable running gear such as motor driven self-laying tracks. On the frame, a boom is mounted for vertical as well as horizontal swinging movement, power means being provided on the frame for controlling the horizontal and vertical adjustments and positions of the boom. The boom carries a drag line scraper by means of a hoist line extending out over the boom and down to the scraper and a drag line or hauling line extending from the scraper inwardly under the boom, both lines being controlled by suitable motor driven drums mounted on the frame of the back filler and to which they are connected. As the boom swings vertically and horizontally or laterally, the lead or angle of the hoist line from the machine out to the outer and upper end of the boom changes. It has been the practice and it is practically a necessity to provide guide means on the frame of the machine for the hoist line at a point where it leaves the frame and travels out over the boom. This guide means in its most practical and successful form consists of guide rollers between which the hoist line extends. In order to obtain the proper guiding action and to minimize wear on the hoist line, the axes of the guide rollers should always be substantially at right angles to the hoist line. It is difficult to maintain this relation between the hoist line and the guide rollers because of the swinging movements of the boom.
- One of the principal objects of the present invention is to provide guide means or the so-called fair lead for the hoist line of a back filler which is readily adjustable to maintain the guide rollers of the fair lead at right angles to the hoist line, thus providing for proper control of the hoist line and minimum wear thereon.
- Another object is to provide a fair lead of this character which is effective to guide the hoist line and properly deflect the same both vertically and horizontally and which is of simple and durable construction, reliable in operation and easy and comparatively inexpensive to manufacture and apply.
- In carrying out the present invention a fair lead for a hoist line of a back filler is provided which consists of a main frame or bracket secured to the A-frame of the back filler and carrying a pair of horizontally disposed guide rollers. In advance of these guide rollers an adjustable frame is mounted on the main frame for tilting or swinging movement and carries a plurality of so-called vertical guide rollers. Co-operating means is provided between the main frame and the swinging frame for securing the swinging or tilting frame in any one of a plurality of adjustments. When the tilting frame is adjusted the position or angle of the rollers carried thereon is varied. The hoist line extends between the horizontal rollers and also between two of the vertical rollers of the tilting frame; and the vertical rollers are adjusted to follow the working angles of the hoist line. In other words, the vertical rollers may always be maintained substantially at right angles to the hoist line. By providing three vertical rollers the fair lead is also adapted for use with a clam shell bucket.
- Other objects and advantages reside in certain novel features of the construction, arrangement and combination of parts which will be hereinafter more fully described and particularly pointed out in the appended claims, reference being had to the accompanying drawings forming a part of this specification, and in which:
- Figure 1 is a fragmentary view in elevation illustrating how the hoist line fair lead is applied to the back filler;
- Figure 2 is a view of a hoist line fair lead in side elevation;
- Figure 3 is a view partly in front elevation and partly in section; and
- Figure 4 is a sectional view taken on line 4-4 of Figure 2.
- Referring to the drawings, the numeral 1 designates generally the main frame of a

100

back filler equipped as usual with the conventional A-frame 2. A boom 3 is provided and is supported on the main frame for vertical and horizontal swinging movement. 5 The vertical swinging movement of the boom is controlled by hoisting tackle 4 of well-known construction. The drag line scraper, designated at 5, is carried at the lower end of the hoist line 6 which runs up 10 over a pulley 7 at the outer end of the boom and then back through the hoist line fair lead 8 constituting the present invention, after which it passes on to the usual power driven drum on the main frame. A drag line or hauling line 10 is also connected with the scraper 5 in the usual manner and passes from the scraper back to its power driven drum under the control of a drag line fair lead 11 forming the subject matter of a co-pending application of Robert L. Brown, 15 Serial No. 248,287, filed January 21, 1928.

The hoist line fair lead constituting the present invention comprises a suitable main frame or bracket which may consist of side 25 plates 15 bolted or otherwise suitably secured to a cross member 16 riveted or otherwise appropriately fastened to the A-frame 2. On the lower portions of the bracket plates 15 a pair of horizontal guide rollers 17 are 30 rotatably mounted. Each guide roller 17 includes a shaft or axis 18 extending between and fixed to the side plates 15 and on which a roller body 19 is mounted for free rotation by means of ball bearings 20.

In advance of horizontal rollers 17, a tiltable frame designated generally at 25 is provided, the tilttable frame including side members 26 and upper and lower cross members 27. The side members 26 are provided

40 with opposed and aligned bearing openings 28 which receive trunnions of studs 29 supported on the plates 15. As shown in Figure 3 these trunnions 29 may consist of short studs or bolts threadedly connected as

45 at 30 with the side plates and held in adjustment by virtue of the frictional engagement of their heads 31 with suitable washers 32. The portions of these studs which fit in the openings 28 are round and smooth to permit 50 of free tilting of the frame 25. A plurality, preferably three, upright or vertical rollers 35 are mounted for free rotation on the tilttable frame 25.

While these rollers 35 are frequently positioned at more or less of an 55 angle to the vertical, they are referred to in the industry as vertical rollers and they will be so termed in this specification with the understanding that they are usually somewhat angled to the vertical. Each of these

rollers includes a shaft or axis 36 fixedly secured to and supported on the upper and lower cross members 27 of the tilting frame and a roller body 37 supported for free rotation on the shaft 36 by virtue of the inter-positioning of the ball bearing assemblies

38 between the roller bodies and the shafts 36. The roller bearing assemblies engage shouldered portions 36a of the shaft 36 to prevent endwise displacement of the roller bodies 37 in either direction. Outside of the 70 roller bearing assemblies dust excluding devices are provided and include sleeves 40 loosely mounted on the reduced ends of the shaft 36 and felt washers 41 fitted in internal recesses provided in the ends of the roller bodies and extending to and engaging the 75 loose sleeves 40.

Means is provided for releasably holding the tilting frame 25 in any one of a plurality of angular positions or adjustments. This means consists of a lock rod 45 adapted to be inserted through the apertures of ears or lugs 46 provided on the tilting frame 25 and through any one of a number of opposed sets of apertures 47 provided in the side plates 15 of the fixed frame. As clearly shown in Figure 2, the apertures 47 are arranged in arcuate series with respect to the axis or rotation of the tilting frame so that the apertured ears or lugs 46 of the 80 tilting frame may be brought into alignment with any set of aligned openings 47 when the lock rod is removed. When the lock rod is inserted through the aligned openings 47 and the aligned ears or lugs 46 of the 85 tilting frame may be brought into alignment with any set of aligned openings 47 when the lock rod is removed. When the lock rod is inserted through the aligned 90 openings 47 and the aligned ears or lugs 46 it holds the tilting frame in adjusted position. A cotter pin 48 may be provided to prevent endwise displacement of the lock rod 45 in one direction. Any appreciable endwise displacement of the lock 95 rod 45 in an opposite direction is prevented by angularly bent end 50 thereof which also serves to facilitate manipulation of the lock rod.

The hoist line 6 extends in between the 105 horizontal rollers 17 and in between two of the vertical rollers 35. In order to prevent the lines or cables passing through the rollers 35 from dropping down below the lower edge of the rollers 35 in any adjustment of the boom the lower ends of the side members 26 of the frame have outward extensions 55 carrying a cross rod 56 on which a sleeve 57 is loosely mounted. Thus when a line or cable tends to drop down below 110 the lower ends of the rollers 35 it is engaged by the sleeve 57 and held against further downward movement thereby so as to be thus constrained to run between the lower 115 portions of the rollers 35.

With this construction, whenever the boom is raised or lowered, the tilting frame 25 may be tilted or swung in one direction or the other about its trunnions 29 to position the rollers 35 at right angles to the working angle or the direction in which the hoist line 6 extends. The lock rod 45 is readily removable to prompt this adjustment of the tilting frame and when inserted 120 125 130

serves to maintain the tilting frame in the selected adjustment.

By providing both horizontal and vertical rollers the deflection of the cable either horizontally or vertically is controlled by the rollers 17 and 35 and sharp bending of the cable is avoided and wear thereof is minimized.

While adapted for advantageous use with backfillers, the fair lead is not restricted to this particular application, but may be used to advantage with various excavating machines except those of the full revolving type.

15 The invention claimed is:—

1. A hoist line fair lead for use with an excavating machine having the usual hoist line and a vertically and laterally swingable boom with which the hoist line coacts and comprising a number of rollers engageable with the hoist line, mounting means supporting the rollers for rotation and for bodily tilting movement about a horizontal axis, and means for releasably securing the 20 mounting means in various adjustments whereby the rollers may be maintained substantially at right angles to the line when the boom is adjusted up and down.

2. A hoist line fair lead for use with an excavating machine having the usual hoist line and a swingable boom with which the hoist line co-acts, and comprising a fixed frame, a tiltable frame mounted on the fixed frame, means for releasably securing the 35 tilting frame in any one of a plurality of adjustments, and guide rollers rotatably supported on the tiltable frame and engaging the hoist line.

3. A hoist line fair lead for use with an excavating machine having the usual hoist line and a swingable boom with which the hoist line co-acts, and comprising a fixed frame, horizontal rollers mounted on the fixed frame and engaging the hoist line, a 40 tiltable frame mounted on the fixed frame, means for releasably securing the tilting frame in any one of a plurality of adjustments, and guide rollers rotatably supported on the tiltable frame and engaging the hoist line.

4. A host line fair lead for use with an excavating machine having the usual hoist line and a co-operable boom swingable up and down and laterally, and comprising a fixed 45 frame, a tiltable frame mounted on the fixed frame, means for releasably securing the tilting frame in any one of a plurality of adjustments, guide rollers rotatably supported on the tiltable frame, and means on the tiltable frame for preventing the hoist line from dropping down below the guide rollers.

5. A hoist line fair lead for use with an excavating machine having the usual hoist line and a co-operable boom mounted for up

and down and lateral movement, and comprising a pair of horizontal rollers mounted for rotation about a fixed axis and between which the hoist line extends, a plurality of upright rollers co-operable with the hoist line and means for supporting the upright rollers for tilting movement whereby they may be adjusted to maintain them at the proper angle to the hoist line when the boom is moved up or down.

6. A hoist line fair lead for use with an excavating machine having the usual hoist line and a co-operable boom mounted for up and down and lateral swinging movement, and comprising a fixed frame, a tiltable frame, means for co-acting with the frame for supporting the tiltable frame on the fixed frame for tilting movement, said tilting frame including cross members, rollers supported on the cross members for free rotation, and means for securing the tilting frame in any one of a plurality of angular adjustments.

7. A hoist line fair lead for use with an excavating machine having the usual hoist line and a co-operable boom mounted for up and down and lateral swinging movement, and comprising a fixed frame, a tiltable frame mounted on the fixed frame and including cross members, rollers supported on the cross members for free rotation and engaged with the hoist line, said fixed frame having a series of apertures, said tiltable frame having an aperture adapted to be aligned selectively with apertures of the fixed frame, and a releasable lock element co-operable with the aligned apertures for holding the tiltable frame in any one of a number of angular adjustments.

8. A fair lead of the character described comprising a fixed frame, an adjustable frame pivotally mounted on the fixed frame, means for securing the adjustable frame in any of its adjustments, and guide means mounted on the adjustable frame.

9. A fair lead for cable lines comprising a fixed frame, horizontal guide rollers thereon engageable with the cable line, an adjustable frame mounted on the fixed frame, means for securing the adjustable frame in any of its adjustments and upright rollers mounted on the adjustable frame and engageable with the cable lines.

10. A fair lead for cable lines comprising a fixed frame, horizontal guide rollers thereon engageable with the cable lines, an adjustable frame mounted on the fixed frame, means for securing the adjustable frame in any of its adjustments, upright rollers mounted on the adjustable frame and engageable with the cable lines, and means for preventing the lines from being displaced beyond the ends of the upright rollers.

11. A fair lead of the character described comprising a fixed frame, an adjustable

frame including side members and cross members, trunnions co-operative with the fixed frame and with the side members for supporting the adjustable frame on the fixed frame, means for securing the adjustable frame in any one of a number of positions, and rollers mounted on the cross members of the adjustable frame.

In witness whereof, I, hereto affix my signature.
